UNITED STATES PATENT OFFICE

MELVILLE TANNENHOLZ, OF BROOKLYN, NEW YORK

DESIGN FOR A LUNCHEON MAT FOR HOT PLATES

Application filed March 1, 1929. Serial No. 30,279. Term of patent 3½ years.

To all whom it may concern:

Be it known that I, MELVILLE TANNENHOLZ, a citizen of the United States of America, residing at Brooklyn, in the county of Kings and State of New York, have invented a new, original, and ornamental Design for a Luncheon Mat for Hot Plates, of which the following is a specification, reference being had to the accompanying drawing, forming part thereof.

The figure is an elevational view of a luncheon mat for hot plates showing my new design.

I claim:

The ornamental design for a luncheon mat for hot plates as shown.

In testimony whereof I affix my signature.

MELVILLE TANNENHOLZ.
